UNITED STATES PATENT OFFICE.

OTHO C. DURYEA AND MORRIS C. WHITE, OF LOS ANGELES, CALIFORNIA,
ASSIGNORS TO NATIONAL GAS DRILL COMPANY, A CORPORATION OF
CALIFORNIA.

SELF-CONTAINED ROCK-DRILL.

No. 841,001.

Specification of Letters Patent.

Patented Jan. 8, 1907.

Application filed April 28, 1903. Serial No. 154,678.

To all whom it may concern:

Be it known that we, OTHO C. DURYEA and MORRIS C. WHITE, both citizens of the United States, residing at Los Angeles, in the county of Los Angeles and State of California, in the United States of America, have invented a new and useful Self-Contained Rock-Drill, of which the following is a specification.

Our invention relates to a rock-drill which is entirely self-contained and has two connected pistons, or what might be termed a "free-moving double piston," which is reciprocated by the explosion of a suitable fuel.

This invention is characterized by the total absence of fly-wheels, auxiliary motors, cams, or other rotating or inertial devices, cranks, levers, returning-springs, or the like, the engine being unconnected with any mechanical device for operating the piston through a whole stroke or part of a stroke either by inertial effect, by the elasticity of parts, or by any counterbalancing weights. The movement of the piston is entirely unimpeded, and the power from the explosion is utilized to a high degree and applied to the work in a direct manner.

The free piston-engine is adapted to be used for power-hammers, air-compressors, pumps, riveters, chippers, pile-drivers, rock-drills, and other reciprocating tools or machines.

The construction of this engine is such that its movement is under perfect control and may be quickly accelerated or retarded, as desired. The engine has a cushioned stroke and is susceptible of some variation in the length of stroke, which makes the engine particularly adapted for percussive work.

This rock-drill is particularly efficient, as it is self-contained, the mechanism for generating the power being contained entirely within the drill itself, the energy not being produced in extraneous devices, such as required by rock-drills using air-compressors, electric generators, or the like.

Referring to the drawings, Figure I is a transverse sectional view on line I I, Fig. IV. Fig. II is a transverse sectional view taken on line II II, Fig. IV. Fig. III is a transverse sectional view taken on line III III, Fig. IV. Fig. IV is a longitudinal sectional view through the invention applied as a rock-drill, the electrical connection for operating

the sparker being shown in diagram. Fig. V is a horizontal sectional view taken longitudinally through the drill. Fig. VI is a transverse sectional view taken on line VI VI, Fig. IV.

In the form shown this rock-drill comprises tandem cylinders 1 and 2, which are mounted on a casing 3. Pistons 4 and 5 in cylinders 1 and 2 are connected by a piston-rod 6, which carries a yoke 7, the latter being connected with a socket-shank 8 by means of slide-rods 9 and a front yoke 10. 11 and 12 are inlet puppet-valves for compression-chambers 13 and 14, respectively, and the explosive mixture is supplied to the puppet-valves from a passage 15, which communicates with an inlet 16, as shown in Figs. I and VI. The explosive mixture is sucked alternately into the compression-chambers 13 and 14, and as the respective pistons reciprocate they open and close ports 17 and 18 alternately, and the explosive mixture is thus admitted alternately into cylinders 1 and 2 and there compressed and ignited from sparking plugs 19 and 20.

The compression of the explosive mixture within the cylinders cushions the stroke after the manner set forth in our copending application, Serial No. 100,302, filed March 27, 1902, in which we have claimed certain features of invention shown herein, but not herein claimed for the reason that same are claimed in said application. In said application we have shown a cylinder, a piston therein, a second cylinder axially in line with said first cylinder, a second piston in said second cylinder, a rod connecting said pistons, a yoke carried by said rod, tool-carrying means axially in line with said cylinder, a head carrying said tool-carrying means, a connection between said head and said yoke, and means for causing an explosion of gases against first one piston and then the other piston to reciprocate said piston and its attached parts, and a casing carrying said cylinders is slidably mounted in a frame and moved therein by a screw, as shown in this application; but no claim to the structure shown in said former application is made herein, for the reason that the same is claimed therein, this application being for an improvement over the subject-matter of said former application. After the ignition the ex-

ploded mixture passes from the cylinders alternately through outlet-ports 21 and 22 as soon as the respective pistons move past and open the respective ports 21 and 22. The outlet-ports 21 and 22 communicate with outlet-passages 23 and 24, respectively. (See Figs. VII and VIII.) As the charge of fuel passes into cylinders 1 and 2 through ports 17 and 18 each charge is deflected by curved wings 25 and 26 toward the heads of the cylinders and drives out the product from the previous explosion. The respective outlet-ports 21 and 22 lie nearer the heads of their respective cylinders than do the inlet-ports 17 and 18. This allows much of the exploded gases to exhaust from the cylinders before fresh charges enter.

27 designates oil-tubes for the respective cylinders. Spark-coils 28 and 29 are provided for the sparking plugs 19 and 20, one pole of the secondary of a coil being connected to its sparking plug while the other pole is grounded to the frame. One pole of the primary of a coil is grounded to the frame of the drill, the other pole being connected to a spring-contact within the casing 3. The primary of the coil 28 is connected to contact 30, while the primary of coil 29 is connected to contact 31. As the yoke 7 reaches the end of each stroke it carries a blade 32 into contact with one or the other of the spring-contacts 30 and 31. When the blade 32 contacts with contact 30, it closes the primary circuit through coil 28 and produces a spark at sparking plug 19, while when it is in contact with contact 31 it closes the primary circuit through coil 29 and produces a spark at sparking plug 20. Thus impulses are given alternately to the pistons, one explosion at each end of the stroke.

The socket-shank 8 is revolvably mounted in the front yoke 10, as shown in Figs. IV and V, and is rifled, as at 33. The rifled portion of the socket-shank is mounted in a correspondingly-rifled ratchet 34, which is rotatably mounted in the end of the front of the casing 3. Pawls are pivoted in recesses in the casing 3 and engage the ratchet 34 and prevent rearward rotation of the ratchet 34, and as the socket-shank is reciprocated in one direction by reason of the friction between the socket-shank and front yoke 10, together with the stability of the socket-shank, it turns the ratchet forward as the rifled portion of the socket-shank slides through the socket-shank. When the socket-shank slides in the opposite direction, the pawls 35 prevent rearward movement of the rifled ratchet 34, which causes the socket-shank 8 to be partially rotated as it is retracted, and the tool attached to the socket-shank is thereby turned step by step during the work.

Both cylinders are suitably water-jacketed, as at 36, and in order to supply water to cool

the tool the socket-shank may be made hollow, as shown in Figs. IV and V. A stationary tube 37, one end of which may communicate with the water-jacket 36, may be slidably fitted within the hollow socket-shank 8 and will convey water from the water-jacket 36 to the interior of the socket-shank and thence to the tool. In working the socket-shank freely telescopes with the tube 37.

The casing 3 may be slidably mounted in ways formed in a stationary frame 38 and may be moved back and forth along the frame 38 by means of a screw 39, which is swiveled in a bar 40, supported by rods 41, which project from the casing 3.

Projecting from the end of the yoke 7 is a handle 45, which may be used in giving one or two reciprocations in starting the drill, the shank of the handle 45 sliding in a slot 46, formed in the side of the wall which incloses the space between the two compression-chambers. The space between the two compression-chambers at the top may be provided with a removable cover 47, and by removing the same access may be had to the interior. The piston-rod 6 is preferably fastened to the yoke 7 by being provided with screw-threads 48, which are received by the yoke.

49 is a taper-pin which passes through the yoke and piston-rod 6.

50 is a flange on the piston-rod 6, against which the yoke abuts.

The heads of the compression-chambers 13 and 14 receive threaded plugs 51 and 52, respectively, and the plugs are provided with threaded stems, which carry packing-boxes 53. The plugs 51 and 52 may be removed when it is desired to take the pistons out, the cylinder 1, with its compression-chamber 13, having first been detached from the frame.

54 is a threaded sleeve which is carried in the lug 55, which depends from the casing 3. The screw 39 passes through the sleeve 54, and when the drill is fed by hand the sleeve 54 will tightly fit the lug 55 and will be stationary. When the drill is fed automatically, the sleeve 54 will be revolvably mounted in the lug 55 and will be rotated by suitable mechanism.

What we claim, and desire to secure by Letters Patent of the United States, is—

1. A pair of cylinders, pistons therein, reciprocating means rigidly connecting the pistons, a casing connected with the cylinders, a socket-shank rotatably mounted and connected to reciprocate with said reciprocating means, a rifled sleeve rotatably mounted in said casing, spiral ribs on the socket-shank slidably in the rifled sleeve, means for confining the rotation of the sleeve to one direction and means for causing explosions against said pistons to drive them in one and the other direction.

2. A pair of cylinders, pistons therein,

- means connecting the pistons, a casing connected with the cylinders, means for causing explosions against the pistons to drive the same in one and the other direction, a rifled 5 ratchet rotatably mounted in the end of the front of the casing, a rifled socket-shank rotatably mounted in means connected with the pistons, and means for confining the rotation of the ratchet to one direction.
- 10 3. A pair of cylinders, means for causing explosions against the pistons to drive the same in one and the other direction, pistons therein, a piston-rod connecting the pistons, a yoke attached to the piston-rod, a casing 15 extending forward from the front cylinder, a pair of slide-rods connected to said yoke, a front yoke inside of said casing connected to said slide-rods, a socket-shank rotatably mounted in the front yoke, a rifled ratchet rotatably mounted in the front end of said casing, spiral ribs on the socket-shank passing through the rifled ratchet and means for confining the rotation of the ratchet to one direction.
- 20 4. A pair of cylinders, explosion-chambers communicating therewith, pistons in the respective cylinders, means for causing explosions against the pistons to drive the same in one and the other direction, a piston-rod connecting the piston, screw-plugs in the walls of the respective explosion-chambers concentric with said piston-rod a yoke connected with the piston-rod between the plugs, a

shank connected with said yoke, and means for intermittently rotating the shank.

5. A pair of cylinders, explosion-chambers communicating therewith, pistons in the respective cylinders, means for causing explosions against the pistons to drive the same in one and the other direction, a piston-rod connecting the piston, screw-plugs in the wall of the respective explosion-chambers concentric with said piston-rod, said plugs being provided with threaded stems and a packing box screwed to each of said stems a shank, 45 means connecting the shank with the pistons, and means for intermittently rotating the shank.

In testimony whereof I have signed my name to this specification, in the presence of 50 two subscribing witnesses, at Newark, in the county of Essex and State of New Jersey, this 27th day of April, 1903.
